HOT PLATE

Rollin Stuart Davis, Jr., 32021 Weston Drive,
Birmingham, Mich.

Filed July 5, 1963, Ser. No. 75,683

Term of patent 14 years

(Cl. D44—10)

Fig. 1

Fig. 2

Fig. 4

Fig. 3

Fig. 5

FIGURE 1 is a perspective view of a hot plate showing my new design wherein a single bowl shaped element including a heating coil is employed;

FIGURE 2 is a top view thereof;

FIGURE 3 is a side view thereof;

FIGURE 4 is an end view thereof;

FIGURE 5 is a bottom view thereof;

FIGURE 6 is a top plan view of a modified form of the hot plate of FIGURE 1 wherein a pair of bowl shaped elements including heating coils is employed and wherein the wirestock base takes the form disclosed in this and the following figures;

FIGURE 7 is a side view thereof;

FIGURE 8 is a bottom view thereof; and

FIGURE 9 is an end view thereof.

I claim:

The ornamental design for a hot plate, as shown and described.
